F. B. KING

SPRING CUSHION

Filed Aug. 23, 1920

INVENTOR.
Fred B. King.
BY Chester H. Braselton
Harry W. Lindsey, Jr.
ATTORNEY

UNITED STATES PATENT OFFICE.

FRED B. KING, OF TOLEDO, OHIO, ASSIGNOR TO THE WILLYS-OVERLAND COMPANY, OF TOLEDO, OHIO, A CORPORATION OF OHIO.

SPRING CUSHION.

Application filed August 23, 1920. Serial No. 405,214.

To all whom it may concern:

Be it known that I, FRED B. KING, residing at Toledo, in the county of Lucas and State of Ohio, have invented certain new and useful Improvements in Spring Cushions, of which I declare the following to be a full, clear, and exact description.

This invention relates to improvements in spring cushions for use particularly, although not exclusively, in automobiles. The present invention may be regarded as an improvement over my co-pending application, Serial Number 305,892, filed June 21, 1919.

One of the objects of the invention is the spacing of the spring assembly away from the apron which joins the cushion and the seat base.

Another object is the centering of the lower part of the spring assembly upon the seat base.

Other objects, and objects relating to details of construction and economies of manufacture, will appear as I proceed with the description of that embodiment of the invention which, for the purposes of the present application, I have illustrated in the accompanying drawing, in which:

Figure I is a fragmental perspective view of a portion of a seat base embodying my invention, and shows the manner of attaching the apron as well as one of the lugs by means of which the centering of the spring assembly is accomplished.

Figure II is an elevational view of a complete cushion with certain parts broken away and others shown in section in order to more clearly illustrate the invention.

Figure III is a plan view of a fragment of the seat base showing the apron retaining tongues and the centering lugs in their upright positions, that is, in the positions which they occupy before the assembling of the parts.

Figure IV is a detail, vertical, sectional view of a lower edge of the structure.

Similar reference characters refer to like parts throughout the views.

In the drawing, 10 represents a wire mesh constituting the principal part of the base of the seat, said mesh being attached on all

four of its sides to a lower border frame 11. The attachment may be effected by any suitable means; that shown in the drawing being by welding the ends of each wire to the horizontal portion of the border frame.

The border frame 11 is bent downwardly near its outer edge to form a groove 12, the outer wall of which merges into an upstanding flange 13. The groove 12 is formed for the accommodation of the lower edge of the seat apron 14, extending preferably entirely around the structure. A common method of finishing the lower edge of this apron is illustrated in the drawing, namely, the folding up of the upholstery material on the inside and stitching through the two thicknesses, thereby leaving a loop at the bottom in which is carried a rod, wire or cord 15.

A series of tongues 16 are struck up out of the border frame 11, and before assembly of the parts, stand in vertical position at the inner side of the groove 12. When the lower edge of the apron is in place in the groove, the tongues 16 are bent outwardly and downwardly over the beaded edge of the apron to hold the latter firmly in place.

The upper edge of the apron 14 is also preferably beaded and is attached by suitable means to the periphery of the upholstery material 17. The latter is attached at its edges to a frame member 18 extending entirely around the cushion. This rigid frame prevents the cushion from spreading or losing its original shape. The filling material 19 is packed within the upholstery material 17, no under-cover being required as the spring assembly when put in place serves to prevent the filling from escaping.

In the form of seat structure here illustrated, the springs are assembled together in a unit which is herein termed the spring assembly. It consists of a multiplicity of coil springs 20 retained in pockets formed by stitching transversely at proper intervals the sides of a longitudinally folded strip of cloth 21. Each such strip carries a series of springs sufficient in number to extend substantially across the seat. A number of such strips with their pockets filled with

springs are placed side by side until the distance across the strips is substantially equal to the other dimension of the seat. Then all of these strips containing springs 5 are enclosed in a fabric casing 22 extending around the sides and across the top and bottom of the whole. The periphery of the spring assembly at its lower edge is preferably beaded and for this purpose may 10 contain a cord or wire 23.

Now, in order to space the spring assembly from the apron 14 and also for the purpose of centering the spring assembly upon the seat base, lugs 24 are employed. These 15 extend upwardly from the border frame 11 inwardly of the groove 12 at intervals along all sides of the frame. Preferably these lugs are struck up out of the frame itself, and before assembly of the parts 20 stand vertical. However, the upper ends of the lugs may be, and preferably are, bent inwardly and downwardly after the spring assembly is in place in order to more closely contact with the latter and 25 hold it against movement in every direction.

In assembling a seat built according to my invention the following procedure may be followed: The cushion cover, including the portion 17 and the apron 14, is first attached 30 to the frame member 18. Then the filling 19 is packed in place, the cushion being inverted. Next the spring assembly is mounted within the frame member 18, thereby closing the opening within that frame. Then the 35 inverted seat base is placed over the spring assembly and the lugs 24 bent into contact with the latter. Thereafter the lower beaded edge of the apron 14 is fitted within the groove 12 of the lower border frame 11 and 40 the tongues 16 bent into engagement with the beaded edge of the apron by means of pliers having at least one jaw of a size that will pass through the openings formed in the border frame when the tongues 16 are 45 struck up out of the same. The seat structure is then complete.

I am aware that the particular embodiment of my invention herein illustrated and described is susceptible of considerable variation without departing from the spirit thereof, and therefore I desire to claim my 50 invention broadly as well as specifically as indicated by the appended claims.

What I claim as new and desire to secure 55 by Letters Patent is:

1. In a seat structure, a lower border frame having an inwardly extending flange portion, a spring assembly supported on said flange portion and comprising a multiplicity 60 of coil springs, means for holding the springs together and in proper position relative to the load and to each other, and lugs struck up from said border frame and adapted to engage the exterior of said spring assembly and to be bent inwardly into contact there-

with to center the latter upon the lower border frame.

2. In a seat structure, a lower border frame having at its inner periphery a supporting flange portion and having means 70 near its outer periphery for retaining the lower edge of the seat apron, a spring assembly comprising a multiplicity of coil springs on the said flange portion and means for holding the springs together and in 75 proper position relative to the load and to each other, and lugs extending upwardly from an intermediate portion of said border frame for engaging the exterior of said spring assembly and for centering and spacing the 80 same from said apron.

3. In a spring seat, a frame including a horizontally disposed border portion, tongues extending upwardly from said border portion intermediate its edges, and a unitary 85 seat element comprising a support and a plurality of springs secured thereon, said seat element being insertable upon and supported by the frame independently of said tongues and adapted to be centered upon the frame 90 by the tongues.

4. In a spring seat, a frame including a horizontally disposed border member, tongues extending upwardly from said border member intermediate its edges, a unitary 95 seat element comprising a support and a plurality of springs secured thereon, said seat element being insertable upon the frame and supported thereby independently of the tongues, said tongues serving to hold the 100 seat element centered upon the frame, and an upholstery covering for said seat element including an apron extending downwardly and secured to said border member.

5. In a spring seat, a frame comprising a 105 horizontally disposed border member and a plurality of transverse connecting members, a seat element comprising a support and a plurality of springs secured thereon, said seat element being insertable upon and removable from the frame as a unit and adapted 110 to be supported thereby, and a plurality of tongues extending upwardly from said border member between the edges thereof and adapted to form guides for centering 115 the seat element upon the frame.

6. In a spring seat, a spring structure comprising a plurality of coil springs, a fabric covering therefor having a lower beaded edge, a support for said spring structure 120 comprising a border frame having a substantially horizontal inner portion and a series of lugs struck up therefrom, said lugs surrounding and engaging over said beaded edge to center and retain said spring structure.

7. In a spring seat, a spring structure comprising a plurality of coil springs, a fabric covering therefor having a beaded edge, an apron surrounding, said spring structure, 130

a support for said structure comprising a border frame and a wire mesh attached thereto, said frame having a flat inner peripheral portion for carrying said mesh and having an outer upturned edge portion, a series of lugs struck up from said border frame and clamping said apron to said edge portion and a series of lugs struck up from said border frame and engaging the beaded edge of said fabric covering to center and retain the spring structure thereon. 10

In testimony whereof, I affix my signature.

FRED B. KING.
